TRANSPARENT LIQUID LENS MICROSCOPE

Carl F. Berger, Livonia, Mich., and Harold T. Neuberger,
South Casco, Maine, assignors to Houghton Mifflin
Company, Boston, Mass.

Filed Nov. 12, 1973, Ser. No. 414,871

Term of patent 14 years

Int. Cl. D16—06

U.S. Cl. D57—1 E

FIG 1

FIG. 2

FIG. 3

FIG. 4

FIG. 5

FIG. 6

FIG. 7

FIG. 1 is a perspective view of a transparent liquid lens microscope, showing our new design;

FIG. 2 is a front elevational view thereof;

FIG. 3 is a rear elevational view thereof;

FIG. 4 is a side elevational view;

FIG. 5 is an elevational view of the other side thereof;

FIG. 6 is a bottom plan view thereof; and

FIG. 7 is a top plan view thereof.

We claim:

The ornamental design for a transparent liquid lens microscope, as shown.
